DIETRICH MÜLLER-HILLEBRAND, OF BERLIN-CHARLOTTENBURG, GERMANY, ASSIGNOR
TO WESTINGHOUSE ELECTRIC & MANUFACTURING COMPANY, A CORPORATION OF
PENNSYLVANIA

HIGH TENSION APPARATUS

Application filed April 21, 1928, Serial No. 271,722, and in Germany April 22, 1927.

My invention relates to a high-tension apparatus composed of a plurality of individual parts, in which metallic members are arranged between the high-tension electrodes. The object of my invention is to increase considerably the flashover voltage of such apparatus.

In the drawings affixed hereto and forming part of my specification are illustrated two embodiments of my invention.

In the drawings:

Fig. 1 is a sectional side-elevation of an upright porcelain support, and

Fig. 2 is a rotary type disconnecting or isolating switch in elevation, to which my invention is applied.

It is well known that the flashover voltage between two electrodes of electric high-tension apparatus is lower than corresponds with the sparking distance, if metal parts are located in air between the electrodes. The reason is that such metal parts represent intermediate electrodes. In the case of supporting insulators composed of a plurality of parts metal rings are arranged at the joints and keep the individual ceramic parts of the support together. In the case of rotary disconnecting switches the intermediate electrode consisting of metal is formed by the switch knife mounted on the central one of the three supporting insulators and occupying the open position. In order to increase the flashover voltage in such high-tension apparatus it is necessary to increase the spacing of the electrodes from the intermediate electrodes. At very high voltages comparatively large distances between parts are attained in this way, whereby the space requirement for high-tension apparatus is considerably increased.

According to my invention an increase of the electrode spacing is avoided and an increase of the flashover voltage attained by coating or enveloping the metal parts with an insulating material. In the case of rings, as in the first mentioned example of the supporting insulator, these rings are completely covered with an insulating material. In the case of rotary disconnecting switches the switch knives are covered with an insulating

material almost in their entire length, so that only the ends, which make the contact, project from the insulating material. The parts, which serve for mounting the insulating material upon the metal parts, are likewise constructed of insulating material. As insulating materials there may be employed the known highgrade insulating materials, but also insulating materials of the second order, as long as the insulating capacity suffices for the case in question.

Referring to Fig. 1 of the drawings showing as an example of a high-tension device according to my invention a supporting insulator, it will be seen that this insulator is composed of three ceramic or porcelain parts 2, 3 and 4. The electrodes are formed by the cap 5 and the base 6. On the joints of the individual ceramic parts of the support there are provided metal rings 7 into which the individual parts may be cemented. According to my invention these rings are covered with an insulating layer or covering 8.

In Fig. 2 is illustrated as example for the application of my invention a rotary disconnecting or isolating switch of the usual or any other suitable construction. On a base 10 are mounted the three supporting insulators 12, 13, 14. The central support, 80 which carries the switch knife 17, can be turned from the closed position shown in the drawing into the open position by turning the shaft 11. According to my invention the knife 17 of the switch is covered 85 with or enclosed by a layer of insulating material.

Various modifications and changes may be made without departing from the spirit and the scope of the invention, and I desire, 90 therefore, that only such limitations shall be placed thereon as are imposed by the prior art.

I claim as my invention:—

1. In combination, in outdoor high-volt- 95 age apparatus, spaced weather-exposed electrodes, a conducting element therebetween in spaced relation thereto, and means including a dielectric covering on a portion of said element providing closer spacing between 100

the electrodes than is permissible with said portion exposed.

2. In combination, in outdoor high-voltage apparatus, spaced weather-exposed electrodes, a conducting element therebetween movable relative thereto between a position operatively connecting the electrodes and a position spaced therefrom, and means including a dielectric covering on a portion 10 of said element providing closer spacing between the electrodes than is permissible with said portion exposed.

3. In combination, in an outdoor high-voltage switch, laterally-spaced insulating 15 columns, a contact member mounted on one of the columns, a switch arm carried by another of the columns, and means including an insulating cover on said arm providing closer spacing of the columns than is 20 permissible with said arm exposed.

4. In combination, in an outdoor high-voltage switch, laterally-spaced insulating columns, a contact member mounted on one 25 of the columns, a switch arm extending radially into another of the columns, and a tubular insulating element covering the arm from a position adjacent to its column to a position adjacent to a contact portion of the arm for co-operation with said contact 30 member.

5. In combination, in an outdoor high-voltage switch, laterally-spaced insulating columns, a contact member mounted on one 35 of the columns, a switch arm extending radially through another of the columns, and tubular insulating means covering a portion of the arm and extending oppositely from its column.

6. In combination, in an outdoor high-voltage switch, laterally-spaced insulating columns including metal elements, one of 40 said columns embodying a tubular portion having a side opening, a contact member mounted in said tubular portion opposite 45 said opening, and a switch arm carried by another of the columns and having a co-operating contact portion movable through said opening.

In testimony whereof, I have hereunto 50 subscribed my name this 31st day of March, 1928, at Berlin-Siemensstadt, Germany.

DIETRICH MÜLLER-HILLEBRAND.
